UNITED STATES PATENT OFFICE.

JOHN D. IHLDER, OF YONKERS, NEW YORK, ASSIGNOR TO OTIS ELEVATOR COMPANY, OF EAST ORANGE, NEW JERSEY.

ELECTRIC OPERATION OF ELEVATORS.

SPECIFICATION forming part of Letters Patent No. 683,689, dated October 1, 1901.

Application filed April 26, 1901. Serial No. 57,616. (No model.)

To all whom it may concern:

Be it known that I, JOHN D. IHLDER, a citizen of the United States, residing at Yonkers, in the county of Westchester and State of New York, have invented certain new and useful Improvements in the Electric Operation of Elevators, of which the following is a specification.

My invention relates to the electrical operation of elevators by the use of a push-button system; and it has for its object to provide a simple, cheap, and effective system of controlling elevators; and it consists in the various features of construction and arrangement of parts having the general mode of operation substantially as hereinafter more particularly set forth.

My invention relates more particularly to an improvement upon the system of electrical operation of elevators shown and described in my application for Letters Patent, Serial No. 660,873, filed December 6, 1897, and entitled "Electrical operation of elevators by a single push-button system." In that application means are provided whereby with the use of a single push-button or circuit-closer in connection with each floor the elevator-car may be brought automatically to that floor ready for use. Furthermore, by the invention described in that application it is not necessary that the operator should see the car and break the circuit to stop it, as it will automatically stop at the floor to which it is called, and it is not necessary to keep the button closed which has just been pressed, as an ordinary pressure of a few seconds duration is all that is required to call the elevator to the desired floor, regardless of its position. The circuits controlling the operation of the elevator-motor are so arranged that a shorter circuit is provided around each push-button controlled by electromagnets, so that the pressure may be removed from a button; but the controlling-circuit will remain closed until broken by a suitable controlling device. Further, in that system when any one push-button has been pressed to call the elevator a pressure of any of the other push-buttons for calling the elevator will not interfere with its operation. Means are also provided whereby the elevator can be operated from the car by

simply pressing any button, and the circuits are so arranged that if the operator changes his mind and desires to stop at some intermediate floor or at any other position he can instantly do so. The usual safety devices are also used in connection with that system, so that if any door of the well or the door or gate of the elevator-cage is open the circuit is broken and the elevator cannot be moved until the doors are properly closed. Other results are obtained by the invention described in the application referred to by means of which a simple and inexpensive system is provided capable of being operated by a push-button at each floor or in combination with a series of push-buttons on the car, each push-button corresponding to a floor. That invention as well as my improvements thereon, hereinafter to be described, are specially for use in connection with dumb-waiters, freight-elevators, or other moving vehicles in which the operator does not ride, but which it is desired to call or send to any particular floor or position and have it there automatically stopped, regardless of its prior position.

In my former application the arrangement of circuits for controlling the elevator-motor was such that upon the car coming to a stop, whether called or set in motion from a landing-floor or set in motion by the passenger in the car, it could again be started in either direction by means of the push-buttons at the landing-floors or stations or by means of the push-buttons on the car. This operation makes it necessary that the passenger in the car upon arrival at his destination shall at once open the car-door, thereby breaking the motor-controlling circuit by means of a switch, as otherwise the car could be again started from any landing-floor or station push-button.

While my present invention, as shown, embodies substantially the same general arrangement of electrical circuits as shown and described in my application Serial No. 660,873, before referred to, and the ends sought to be obtained are of the same general character as the objects hereinbefore set forth, my improvement consists in so arranging the circuits for controlling the elevator-motor that if the car has been started by a passenger in the car pressing a particular push-button and

the car has come to a stop at the desired landing or station the car is still under the control of the passenger and can only again be started by him and cannot be started or operated from any of the landings or stations unless either a safety button or switch on the car is pressed, which is connected to break the controlling-circuit in such manner as to restore all the controlling apparatus to normal conditions, or else the car door or gate is opened and then closed or a landing-door opened and closed or non-interference switches, hereinafter to be described, opened and closed, in all of which cases the controlling circuit and apparatus are restored to normal conditions to be operated from either the car or the landings or stations. The utility of this arrangement is apparent, in that accidents are prevented and certainty of operation is attained without confusion. On the other hand, my present invention provides means whereby after the car has been set in motion from a floor or station button and has been stopped at the desired station the controlling-circuit is left in such condition that the car may be again set in motion from the same or another floor push-button, and this is so provided to guard against that case where the operator at a particular floor or station calls the car and neglects to use it and fails to open and again close the landing-door, which would result in leaving the floor-button circuits open if the arrangement of circuits were such as described in connection with the push-buttons on the car. It will thus be seen that there are motor-controlling devices connected to the car and stations and that as embodied in the push-buttons there are in any event at least two motor-controlling devices, in combination with means for excluding the starting control of the motor from one controlling device after the car has been started from the other controlling device until the car is stopped and control is restored thereto through suitable means for restoring such control.

My improvements further embody the use of what I term "non-interference" switches in connection with the herein-described system of electrical operation of elevators, there being one of these non-interference switches in each of those branches of the controlling-circuits which control the direction of the rotation of the elevator-motor. These non-interference switches are so arranged that when the circuit for starting the motor in a direction to cause the car to travel upward is closed and the motor is rotating in one direction the non-interference switch in the circuit which would cause the motor to rotate in an opposite direction if closed has been broken. These non-interference switches may be arranged to be closed and opened by any suitable means; but I have shown them operated by what I have termed my "reversing-switch," which changes the motor connections to cause it to rotate in different di-

rections. Connections are shown whereby what I have termed "accelerating-magnets" cut out resistance in the armature-circuit and series field-coils on starting and throw them into the circuit again on stopping the motor.

My improvements, furthermore, consist in arranging switches operated by the accelerating-magnets referred to and connected to the switches which they control, so that after the motor is started the circuits controlled by the push-buttons at the different floors or stations and those controlled by push-buttons on the car are interrupted in such manner as to preclude any possible interference with the operation of the car from a landing or station when the car is being controlled by a passenger.

In the accompanying drawings I have illustrated the circuits and apparatus necessary to accomplish the results described under the general terms of my invention.

In the drawings, Figure 1 illustrates diagrammatically the arrangement of circuits and apparatus in accordance with my invention. Figs. 2 and 3 are respectively side and end views of an electrical reversing-switch. Fig. 4 is a side view of a modification of the reversing-switch, which includes the contacts of the non-interference switches, showing their mode of operation.

In the drawings, A is the shaft of an armature A' of an electric motor, which is the preferred means of operating the elevator-car, the car and connections between it and the armature of the motor for operating it being omitted, as they may be of any well-known or desirable construction, it only being necessary that they are such connections as will move the car in one direction or the other, according to the direction of rotation of the motor.

Any suitably-wound motor may be used to operate the elevator-car; but I have shown one in which A² represents the shunt field-magnet winding, while A³ represents a series winding adapted to increase the torque on starting, but preferably arranged to be subsequently cut out of circuit, thereby reducing the torque, but accelerating the speed of the motor. A⁴ represents a brake-magnet, preferably arranged in a shunt around the motor, by which the ordinary mechanical brake of the elevator-engine is controlled, it being understood that the brake is normally on to prevent the engine operating except when the current is flowing through the magnet A⁴, the brake being then released, but is again automatically applied when the current ceases. For convenience of illustration, a' a² a³ a⁴ a⁵ represent binding-posts on the motor, to which the terminals of the motor-circuits are connected and to which also the circuits leading to and from the motor are connected.

In order to control the circuits of the motor, I make use of substantially the same type of electric reversing-switch B described in my prior application; but this may of course

vary in construction and operation, it only being necessary to be so constructed as to control the circuits of the motor and to be itself controlled by the elevator-operating circuits. I prefer the construction illustrated more fully in Figs. 2, 3, and 4 and indicated in the diagram by similar letters. In the present instance the electric reversing-switch consists, essentially, of two magnets 5 $B' B^2$, arranged opposite each other, with an armature B^3 suspended between the magnets. Mounted in the armature are a number of double-faced contacts $b b' b^3 b^3$, preferably of carbon, and each connected by a 10 suitable conductor to a corresponding binding-post on the top of the armature or otherwise. These double-faced contacts on the armature are arranged to coöperate with similar contacts arranged on either side of the armature and preferably under the magnets, 15 and these contacts are designated for convenience in the present instance as $b^4 b^5 b^6 b^7 b^8 b^9 b^{10} b^{11}$, as indicated in the diagram. The mechanical construction of all of these contacts is preferably the same as described in 20 my former application referred to. In the present instance additional double-faced contacts are shown for my reversing-switch and lettered $b^{12} b^{13}$ and $b^{14} b^{15}$. The construction 25 of a modification of the reversing-switch containing these additional contacts is shown more particularly in Fig. 4, in which b^3 represents a double-faced contact adapted to make contact with b^{11} , held in a socket B^4 , 30 having a stem B^5 , adapted to slide under spring-pressure in the support B^6 . The operation of contacts $b^{14} b^{15}$ being the same as the opposite pair $b^{12} b^{13}$, the construction described for one set applies to both. One of 35 the contacts, as b^{14} , is suitably supported upon an insulating-piece B^7 , while the other contact b^{15} is suitably supported upon an insulating-piece B^8 , carried in any convenient manner by the stem B^5 , so that when the 40 double-faced contact b^3 impinges upon contact b^{11} and moves the spindle in its support contacts b^{14} and b^{15} are separated. Any two 45 opposite sets of contacts in my reversing-switch could be provided with the additional contacts $b^{12} b^{13}$ and $b^{14} b^{15}$; but they are preferably shown for convenience upon two opposite contacts at the end of the switch, while 50 in the diagram of Fig. 1 they are shown entirely separate; but it is to be understood 55 that their operation is substantially as herein described, and they may hereinafter be designated as "non-interference" switches 10 and 11 when their function is more particularly described.

60 While, as before intimated, the electric reversing-switch just described is the preferred form and while I have described it sufficiently to enable its operation to be understood in the present case, I do not herein claim the 65 same.

In order to operate the electric reversing-

switch automatically when any push-button corresponding to any floor or station is operated, I have shown substantially the same means as described in my prior application 70 referred to, and the same will not be again described in detail. The means provided has been termed a "floor-controller" C and is indicated diagrammatically in Fig. 1. It will suffice to say that this controller C is connected in some suitable way to be operated in unison with the motor or the engine of the car; but as this controller and its connections are not part of the improvements embodied in this invention they have not been shown 80 and described. The controller embodies a cylinder or drum C^2 , on the periphery of which I have shown contacts in the form of two semicircles $C^3 C^4$, insulated from each other by suitable insulation C^{10} , being the 85 equivalent of the particular construction set forth in my prior application. There is a brush c normally engaging contact C^3 and connected by a conductor with one of the coils B^9 of one of the magnets $B' B^2$ of the 90 electric reversing-switch B, and there is another brush c' normally bearing on the contact C^4 , connected to the coil B^{10} of the other of the magnets $B' B^2$ of the reversing-switch, and it will be observed that both of these 95 magnets are connected directly to the negative feeding-main at N through a switch L, the function of which may be to limit the travel of the car in either direction; but as this function is not a part of my present improvement this switch will not be further described. It may operate in any usual and desirable manner.

The non-interference switch 11 is placed in the circuit of the magnet-coil B^9 , while the 105 non-interference switch 10 is placed in the circuit of the magnet-coil B^{10} , and in the diagram of Fig. 1 these switches 10 and 11 are so disposed on each side of the reversing-switch B that when a circuit is completed 110 through the magnet-coil B^9 , for instance, the operation of the reversing-switch will cause contact to be broken at non-interference switch 10, thereby making it impossible to energize magnet-coil B^{10} , which might interfere with the control of the motor. On the other hand, should magnet-coil B^{10} be energized the circuit of the magnet-coil B^9 would 115 be broken at non-interference switch 11. Any other suitable means might be provided for 120 preventing the interference of one operating magnet-coil with the other, and I have only shown a particular means which is used, preferably, because of its adaptability to the construction described. When a current flows 125 through one or other of the coils $B^9 B^{10}$, the corresponding magnet $B' B^2$ is energized and the armature B^3 moved to one or the other side to close the circuit between the double-faced contacts and one or the other of the 130 sets of contacts corresponding with the magnet energized, and consequently the circuits

through the motor will be in a direction to cause it to raise or lower the elevator, as required.

Also arranged in connection with the floor-controller are a series of brushes $f' f^2 f^3 f^4$, one for each floor or stopping-place of the elevator-car and numbered to correspond with the stations $F' F^2 F^3 F^4$. Connected to each brush f' to f^4 is a conductor $d' d^2 d^3 d^4$, each including a circuit-making magnet D and each leading to a position corresponding with the respective floors and terminating at the push-button or other switch device for that floor. The armature D' of each of the circuit-making magnets D is connected to a conductor e, leading to the center of the coils of a differentially-wound circuit-breaking magnet E, which normally does not attract its armature, and leading from the stationary contact E' for said magnet is a conductor H, which passes through a switch I, having contacts $i i'$, and passes in the direction of the floors or stations. This conductor has branches $e' e^2 e^3 e^4$ leading to the push-buttons corresponding with the floors, the push-buttons or circuit-closing devices in the present instance being represented by the pins $g' g^2 g^3 g^4$. One end of the double winding of the magnet E terminates in a pivoted armature E², having a spring E³, which normally holds it against the stationary contact E'.

Up to this point the arrangement of circuits for controlling the elevator-motor has been described as being substantially the same as the circuits in my prior application referred to, and while in that application there were push-buttons arranged upon the car to correspond to the landing-floors or stations, as there are also car push-buttons to be herein-after described as pertaining to this invention, in the prior application the circuits for the car and for the car push-buttons were all in parallel with the circuits for the landing or station push-buttons, as they are in this invention; but the point from which the car push-buttons derived their electrical energy was situated upon the controlling-circuit beyond the doubly-wound magnet E—that is, at a point on the circuit intermediate to those points from which the floor or station push-buttons derived their current. In order to carry out the improvements which form the present invention, I connect the circuit through which the car push-buttons are energized at a point on the controlling-circuit intermediate of the coils on the doubly-wound magnet E. Therefore from the point O leads a conductor which passes through the coil of an electromagnet G, the function of which is herein-after to be described. From the coil of the electromagnet G connection is made to a stationary contact G', and from thence a conductor H' leads to a switch I', having the contacts $i^2 i^3$, and from thence a conductor H⁴ leads to the push-buttons on the car. The car push-buttons $g' g^2 g^3 g^4$ are connected in parallel with the station or landing

push-buttons and respectively connect to the conductors leading from the station push-buttons to the circuit-making magnets D. The magnet G, I have termed my "safety-magnet" for reasons hereinafter to appear, and when energized this magnet attracts a spring-controlled armature G³ against a stationary contact G' and closes a circuit through a high resistance R' direct to the negative lead at r. It will be seen that both the circuits described, one including the station push-buttons and the other the car push-buttons, pass, respectively, through switches I I', the contacts $i i'$ and $i^2 i^3$ of which are in any suitable manner connected with but insulated from the back contacts of the switches 1 and 2, adapted to be controlled by the accelerating controlling-magnets M M'. These controlling-magnets M M' are in series with each other and are adapted to be energized by the operation of the reversing-switch B when it is thrown either to the right or left—that is, so thrown as to start the elevator-motor in one direction or the other. The force of the magnets M M' may be regulated by suitable winding, or springs of different tensions may be connected to the back contacts of switches 1 and 2, or any suitable means may be provided whereby one of the switches, preferably 1, will be closed before switch 2. By the closing of switch 1 it will be seen that a resistance R is cut out of the armature-circuit after the motor has started, while upon the closing of switch 2 the series fields are short-circuited, accelerating the speed of the motor after starting. The closing of switches 1 and 2 opens switches I I', which interrupts both the circuit to the station push-buttons and the circuit to the car push-buttons. Also leading from the circuit-breaking magnet E is a conductor H, which passes through a flexible cable to the car and includes in the circuit on the car a push-button g^7 , by means of which the circuit can be broken at any time by a person on the car, and it also includes a car gate or door contact h^7 . The push-buttons in the car are lettered correspondingly to the push-buttons at the floors or stations, and the closure of a push-button on the car corresponding to any floor will close the circuit through the reversing-switch, which will close the circuit through the motor in the proper direction and move the car and the floor-controller. In the circuit of the conductor H are also placed the circuit-breakers $h' h^2 h^3 h^4$, controlled by the doors of the well corresponding to the different floors, and this conductor H extends to and is connected with the positive main.

I will now explain briefly the operation of the apparatus when a floor or station push-button is pressed, assuming that the doors to the well are all closed, closing the contacts $h' h^2 h^3 h^4$, and assuming, for instance, that the elevator is at the bottom of the well and it is desired to cause it to rise to the top floor F⁴. The button g^4 is pressed for an instant, clos-

ing a circuit which may be traced as follows: Current entering the conductor H from the positive main passes through the door contacts h' to h^4 , then through the flexible cable to 5 the car-gate switch h^7 , through safety or stop push-button g^7 , back through the flexible cable, and by conductor H to the circuit-breaking magnet E, through both coils of that magnet, which coils are wound in opposition to 10 the spring-controlled armature E^2 . The armature E^2 , being kept normally in contact with the stationary contact E' , makes a closed switch through which the current passes to interrupting-switch 1, then still by conductor 15 H in the direction of the floor or station push-buttons, thereby supplying current to the parallel circuits of the floor push-buttons. Floor push-button g^4 being closed, the current passes to the conductor d^4 , to the core of 20 the corresponding circuit-making magnet D, thence through the coil of that magnet, and to the brush f^4 , bearing on the contact C^4 . Thence the current passes to the brush c' through the coils B^{10} of the electric reversing- 25 switch B, and from thence passes through the closed contacts of non-interference switch 10 to one side of limit-switch L and from there to the negative main at N. This energizes one of the magnets of the electric reversing- 30 switch, moving the armature B^3 thereof in the proper direction, causing its double-faced contacts b b' b^2 b^3 , respectively, to make contact, say, with the contacts b^8 b^9 b^{10} b^{11} , thus closing the circuit of the motor, which may 35 be traced as follows: from the plus main through the contacts b b^8 to binding-post a , whence a branch includes the shunt field-coils A^2 , the circuit of which passes to the negative main through the binding-post a^3 . From 40 post a a conductor extends to the point a^7 , so that the current passes from a^7 through a starting resistance R to binding-post a' , from thence through the series field-coils A^3 to post a^2 , thence through contacts b' b^9 to post a^4 45 and brush S of the motor, through the armature to brush S' , thence from post a^5 through contacts b^{10} b^2 to the negative main, thus causing the motor to rotate in a certain direction to raise the elevator. A branch, including 50 the brake-magnet A^4 , extends between the points a^8 and N' , so that the brake-magnet is only energized when the circuit of the motor is completed. Rotation of the motor will cause the floor-controller drum to rotate in 55 the direction of the arrow, and it will be seen that the circuit described will be maintained until this drum has rotated sufficiently to allow the brush f^4 to come upon the insulating portion C^{10} between the contacts C^3 C^4 , 60 which will break the circuit at the magnet B^{10} , releasing the armature of the reversing-switch and stopping the motor. In order to overcome the necessity of holding the push-button g^4 in contact position and in order to 65 prevent interference with the elevator when it is once started, the circuits are arranged so that immediately on completion of the circuit

closed by the push-button g^4 the circuit-making magnet D attracts its armature D' , making a parallel and shorter circuit through the door-contacts h' to h^4 , conductor H, through one coil s only of the circuit-breaking magnet E, and the armature and coils of the circuit-making magnet D, thence through the brush f^4 , and out as before. One of the coils of the 70 differentially-wound circuit-breaking magnet E is therefore short-circuited and the core becomes magnetized, attracting its armature E^2 and breaking the circuit through conductor H, leading to the push-button, and as soon as 75 this is accomplished the button may be released; but the controlling-circuit will be maintained closed at the circuit-making magnet D until finally broken at the desired moment by the floor-controller C when the car 80 reaches its destination. If in the meantime any of the bush-buttons, as g^2 g^3 , is operated, the circuit cannot be completed so as to interfere with the travel of the car. When the car arrives at the desired floor, if the door of 85 the well is opened, breaking the contact h^4 , it will be obvious that the car cannot be started until such contact is closed. It is also obvious that in order to prevent any one at an intermediate floor from opening the door well-known contrivances may be used which will 90 prevent the opening of the door except when the elevator-car is opposite thereto. If then the elevator, being at the top floor, should be desired at any other floor and the corresponding push-button is pressed and the well-doors being closed as before, the circuit will be completed as before, except that the reversing-switch will be operated to close the circuit through the motor to cause it to move the elevator-car in a downward direction, and when it has once started the push-button may be 95 released and no one can interfere with the operation of the elevator until it reaches its destination. 100

It will be seen that when the controlling-circuit is broken by the floor-controller when the car has arrived at the desired point magnet E becomes deenergized and allows its armature E^2 to again assume its normal position 105 in contact with the fixed contact E' , so that the circuit is ready to be made again by pressing any particular push-button. In other words, after the car has been called by operation of a floor-station push-button and has 110 been brought to a stop at its destination it is still under control from any one of the landings or stations provided the well-doors are closed, which close the switches h' to h^4 . 115

As hereinbefore stated, my improvement 120 consists, primarily, in so arranging the motor-controlling circuits that if a car has been started by a passenger in the car pressing a particular push-button and the car has come to a stop at the desired landing or station the 125 circuits remain under the control of the passenger and the car can only again be operated by him and not from any one on a landing or station unless, as described, a landing

door or the car-door has been opened and closed or the stop or safety switch on the car has been pressed, which open-circuits all points of the controlling-circuits and restores all the apparatus to normal positions. I will therefore now explain briefly the operation of the apparatus when a push-button on the car is pressed to cause the car to travel to a particular point and show why it is that after the car has then been brought to a stop it remains under the control of the car operator only. Assuming that the landing - door switches h' to h^4 are closed, that the car-gate switch h^5 is closed, that the safety or stop switch on the car g^7 is closed, and assuming that the car is at the bottom of the well and it is desired to cause it to rise to the top floor F^4 , the button g^4 on the car should then be pressed for an instant, and assuming this to have been done a circuit will be closed as follows: Current entering the conductor H from the positive main passes through the door-contacts h' to h^4 , then through the flexible cable to the car-gate switch h^7 , through safety or stop push-button g^7 , back through the flexible cable, and by conductor H to the circuit-breaking magnet E ; but instead of passing through both coils of this magnet it passes through but one coil s to the point O , and from thence through the coils of the safety-magnet G to the stationary contact G' , thence by conductor H' to interrupting-switch I' , through the switch, and by conductor H^4 to the flexible cable and to the car push-button g^4 pressed, from thence back through the flexible cable, and by conductor d^4 to the core of the corresponding circuit-making magnet D , and through the coil of that magnet to the brush f^4 , and from thence the course of the current and the operation of the circuit-controlling apparatus are as before described when the floor push-button g^4 was pressed to call the car upward.

Returning to the operation of the safety-magnet G , it will be seen that the coils of this magnet have become energized, which causes it to attract its spring-controlled armature G^8 against the fixed contact G' , and thus close a short circuit through a high resistance R' directly to the negative main at r . Since the current has branched at the point O , when the armature D' of a circuit-making magnet D is attracted against its core it is generally found necessary to insert a compensating resistance R^2 in the controlling-circuit between the point O and the negative main, for convenience of illustration this compensating resistance R^2 being shown in the circuit between the point O and a magnet D . The resistance R^2 is so adjusted as to balance the resistance R' when in circuit with the safety-magnet G , so that the circuit through the safety-magnet remains continually closed when its coils are once energized. It will be observed that since but one coil s of the circuit-breaking magnet E is energized in this described case of operating the car

from a car push-button magnet E will here at once attract its armature E^2 , so that it will be impossible to interfere with the operation of the car by the closure of a landing or station push-button. When the circuit for controlling the motor is broken at the floor-controller to stop the car at a particular floor or landing, there still remains a closed circuit through which current is flowing, including the coils of the circuit-breaking magnet E , which may be traced as follows: from the landing-switches h' to h^4 through conductor H , through the flexible cable to gate-switch h^7 and safety-switch g^7 , back by conductor H , through the flexible cable to the coils of the magnet E , thence through the coils of safety-magnet G , contact G' , and armature G^8 , which latter is maintained against contact G' , thence through resistance R' to the negative main at r . Therefore, since current is supplied to the push-buttons on the car through the branch conductor H' , which taps onto the stationary contact G' , and through conductor H^4 it is seen that the car is only under the control of a passenger by means of the car push-buttons, for since the coils of the magnet E maintains the floor - push - button circuit broken between the armature E^2 and contact E' it will be obvious that the car cannot be operated from any landing or station push-button.

In order to prevent with certainty the possibility of interference with the operation of the motor from a landing when it is being operated from the car, and vice versa, the switches I I' have been provided, I being in the circuit which supplies the landing push-buttons with current and I' being in the branch which supplies the car push-buttons with current. The contacts of these switches are operated by the back contacts k k' of the switches I I' . Suitable insulated connections are made between the contacts i i^2 and the back contacts k k' , so that the contacts i i^2 are moved with the back contacts k k' . Contacts k k' are adapted to be moved successively to close the switches I I' by the accelerating-magnets M M' , switch I being preferably closed before switch I' . Magnets M M' are shown in series with each other and derive their energizing-current from the contacts b^9 b^8 on the electrical reversing-switch B , they being preferably arranged, as will be seen, in a shunt directly across the armature, so that they will become energized to attract their armatures after the motor has come up to speed. Suitable electrical connection is made, so that when switch I is closed resistance R is cut out of the armature-circuit, but other suitable connections could be made whereby more or less of the resistance is cut out of the armature-circuit at any one time or successively, I having shown the whole resistance as being cut out at once for simplicity's sake only. The connections and apparatus, as before stated, are so arranged that when switch I' is closed the series coils are cut out of circuit, the magnet M' being

so adjusted that it will operate at the desired time after the motor has started, and the speed of the motor is then accelerated.

By the complete system, as shown and described, for the electrical operation of elevators by a push-button system it is clear that after the car has been operated from any landing or station push-button and has been brought to a stop at the desired station by a 10 breaking of the controlling-circuit at the floor-controller all of the necessary parts for again operating the car will have resumed their normal positions, so that the car is still under the control of any one on the landing or station. 15 On the other hand, it is clear that after the car has been operated by the closure of a push-button on the car and the circuit controlling the motor has been broken at the floor-controller, bringing the car to a stop at its destination, certain parts of the controlling apparatus connected with the breaking-magnet E and the safety-magnet G will not have resumed their normal positions, which normal position is necessary to enable the car to be 20 controlled from a station or landing push-button. In other words, in the case where the car has been operated from a car push-button and has come to a stop a particular part of the controlling-circuit, including the 25 circuit of the car push-buttons, still remains closed, while that particular part of the controlling-circuit including the floor or landing push-buttons is maintained in open circuit. Therefore in this case the car cannot be operated from a floor until first that particular part of the circuit remaining closed after the car has stopped has been broken—as, for instance, at a door-switch—to restore the floor-circuit to a normal condition at the circuit- 30 breaking magnet E, and, secondly, the circuit must again be completed at the door-switch broken in order to place all the controlling-circuits in readiness for subsequent 35 operation.

40 Without limiting myself to the precise details of construction shown and described, I claim and desire to obtain by Letters Patent the following:

1. The combination with a motor, car and 45 station, of motor-controlling devices connected to the car and station and means for excluding control of the car from the station, after the car has come to rest, substantially as described.

50 2. The combination with a motor, car and station, of motor-controlling devices connected to the car and station and means for excluding control of the car from the station, after the car has come to rest, until the station control has been restored from the car, substantially as described.

55 3. The combination with a car and operating-motor, of two motor-controlling devices, means for excluding the starting control from 60 one controlling device after the car has been started from the other until the car is stopped

and control is restored and means for restoring said control, substantially as described.

4. In an apparatus for controlling elevators, the combination with an elevator-motor, of 70 push-buttons for each floor or station, push-buttons on the car, corresponding to the several floors or stations, with circuits and connections, including the push-buttons and motor, for controlling the operation of the motor, and means for preventing the subsequent control of the motor from a floor or station, after it has been operated from the car and stopped, substantially as described.

5. In an apparatus for controlling elevators, 80 the combination with an elevator-motor, of push-buttons for each floor or station, push-buttons on the car, corresponding to the several floors or stations, with circuits and connections, including the push-buttons and motor, for controlling the operation of the motor, and means for preventing the subsequent control of the motor from a floor or station, after it has been operated from the car, and the motor has come to rest, substantially as 85 described.

6. In an apparatus for controlling elevators, the combination with an elevator-motor, of a push-button for each floor or station, push-buttons on the car, corresponding to the several floors or stations, with circuits and connections, including the push-buttons and motor, for controlling the operation of the motor, and means for preventing the subsequent control of a motor from a floor or station, both 90 before and after the motor has come to rest, after it has been operated from the car, substantially as described.

7. In an apparatus for controlling elevators, the combination with a motor for operating 105 the car in either direction, of a push-button for each floor or station, push-buttons on the car, corresponding to the several floors or stations, and controlling-circuits and connections between the push-buttons and the 110 motor, so arranged that when any push-button is operated, circuits are completed and the motor operated to bring the car to the station corresponding to the push-button, and means for preventing the subsequent operation of the motor-car from a floor or station, after it has been started from the car and stopped, substantially as described.

8. In an apparatus for controlling elevators, the combination with a motor for operating 120 the car in either direction, of a push-button for each floor or station, push-buttons on the car, corresponding to the several floors or stations, and controlling-circuits and connections between the push-buttons and the 125 motor, so arranged that when any push-button is operated, circuits are completed and the motor operated to bring the car to the station corresponding to the push-button, and means for preventing the subsequent operation of the motor from a floor or station, both 130 before and after the motor has come to rest,

after it has been operated from the car, substantially as described.

9. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, and means for preventing the subsequent operation of the motor from a floor or station, after it has been operated from the car, and the car has come to rest, substantially as described.

10. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, and means for preventing the subsequent operation of the motor from a floor or station, after it has been operated from the car, until a portion of the controlling-circuits, including the car push-buttons, has been broken and again closed, substantially as described.

11. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, and means for preventing the subsequent operation of the motor from a floor or station, after it has been operated from the car, until a portion of the controlling-circuits remaining energized after the motor has come to rest, has been broken and again closed, substantially as described.

12. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, and means for preventing the subsequent operation of the motor from a floor or station, after it has been operated from the

car, until a portion of the controlling-circuits remaining energized after the motor has come to rest, and including the car push-buttons, has been broken and again closed, substantially as described.

13. In an apparatus for controlling elevators, the combination with a motor for operating the car in either direction, of a push-button for each floor or station, push-buttons on the car, corresponding to the several floors or stations, and controlling-circuits and connections between the push-buttons and the motor, so arranged that when any push-button is operated, circuits are completed and the motor operated to bring the car to the station corresponding to the push-button, and means operating to leave the motor under control from the car only, subsequent to its operation from the car, substantially as described.

14. In an apparatus for controlling elevators, the combination with an elevator-motor, of a push-button for each floor or station, push-buttons on the car, corresponding to the several floors or stations, with circuits and connections including the push-buttons and motor, for controlling the operation of the motor, and means for preventing the subsequent control of the motor from a floor or station, after it has been operated from the car, until a portion of the controlling-circuits, including the car push-buttons, has been broken and closed, substantially as described.

15. In an apparatus for controlling elevators, the combination with an elevator-motor, of a push-button for each floor or station, push-buttons on the car, corresponding to the several floors or stations, with circuits and connections including the push-buttons and the motor, for controlling the operation of the motor, and means operating to leave the motor under control from the car only, subsequent to its starting from the car and its stopping, substantially as described.

16. In an apparatus for controlling elevators, the combination with an elevator-motor, of a push-button for each floor or station, push-buttons on the car, corresponding to the several floors or stations, with circuits and connections including the push-buttons and motor, for controlling the operation of the motor, and means operating to leave the motor subsequent to its operation from the car, under control from the car only, until a portion of the controlling-circuits remaining energized after the motor has come to rest, has been broken and again closed, substantially as described.

17. In an apparatus for controlling elevators, the combination with an elevator-motor, of a push-button for each floor or station, push-buttons on the car, corresponding to the several floors or stations, with circuits and connections including the push-buttons and motor, for controlling the operation of the motor, and means operating to leave the motor subsequent to its operation from the

car, under control from the car only, until a portion of the controlling-circuits remaining energized after the motor has come to rest, and including the car push-buttons, has been 5 broken and again closed, substantially as described.

18. In an apparatus for controlling elevators, the combination with an elevator-motor, of a push-button for each floor or station, 10 push-buttons on the car, corresponding to the several floors or stations, with circuits and connections including the push-buttons and motor, for controlling the operation of the motor, and means for preventing the completion 15 of the motor-controlling circuits from a floor or station to operate the motor, subsequent to their completion from the car, after the car has reached its destination, substantially as described.
19. In an apparatus for controlling elevators, the combination in an elevator-motor, of a push-button for each floor or station, push-buttons on the car, corresponding to the several floors or stations, with circuits and 25 connections including the push-buttons and motor, for controlling the operation of the motor, and means for preventing the completion of the motor-controlling circuits from a floor or station to operate the motor, subsequent 30 to their completion from the car, both before and after the car has reached its destination, substantially as described.

20. In an apparatus for controlling elevators, the combination with a motor for operating the car in either direction, of a push-button for each floor or station, push-buttons on the car corresponding to the several floors or stations, and controlling-circuits and connections between the push-buttons 40 and the motor, so arranged that when any push-button is operated, circuits are completed and the motor operated to bring the car to the station corresponding to the push-button, means for automatically closing a circuit around said push-buttons after one of 45 them has been operated, for preventing interference with the movements of the car, and means for preventing the subsequent operation of the motor from a floor or station after it has been operated from the car, and the car has come to rest, substantially as described.

21. In an apparatus for controlling elevators, the combination with a motor for operating the car in either direction, of a push-button for each floor or station, push-buttons on the car, corresponding to the several floors or stations, and controlling-circuits and connections between the push-buttons and the motor, so arranged that when 55 any push-button is operated, circuits are completed and the motor operated to bring the car to the station corresponding to the push-button, means for automatically closing a circuit around said push-buttons after one of 60 them has been operated, for preventing interference with the movements of the car, and means for preventing the subsequent opera-

tion of the motor from a floor or station, both before and after the motor has come to rest, after it has been operated from the car, substantially as described. 70

22. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, means in the push-button circuits for short-circuiting the push-buttons when any one is closed, thereby preventing interference, 85 and means for preventing the subsequent operation of the motor from a floor or station after it has been operated from the car, and the car has reached its destination, substantially as described. 90

23. In an apparatus for controlling elevators, the combination with a motor for operating the car in either direction, of a push-button for each floor or station, push-buttons on the car, corresponding to the several floors or stations, and controlling-circuits and connections between the push-buttons and the motor, so arranged that when any push-button is operated, circuits are completed and the motor operated to bring the car 100 to the station corresponding to the push-button, means in said push-button circuits for short-circuiting the push-buttons when any one of them is closed, and for breaking the circuit of the floor push-buttons, and means 105 for preventing the subsequent operation of the motor from a floor or station after it has been operated from the car, and the car has come to rest, substantially as described.

24. In an apparatus for controlling elevators, the combination with a motor for operating the car in either direction, of a push-button for each floor or station, push-buttons on the car, corresponding to the several floors or stations, circuit-making magnets 115 for the push-button circuits, and a circuit-breaking magnet controlled thereby, whereby the push-button circuits are short-circuited and the floor-push-button circuit broken, to prevent interference, and means for preventing the subsequent control of the motor from a floor or station, after it has been operated from the car, and the car has come to rest, substantially as described. 120

25. In an apparatus for controlling elevators, the combination with a motor for operating the car in either direction, of a push-button for each floor or station, push-buttons on the car, corresponding to the several floors or stations, circuit-making magnets 125 for the push-button circuits, and a circuit-breaking magnet controlled thereby, whereby the push-button circuits are short-circuited and the floor-push-button circuit broken, 130

to prevent interference, and interrupting-switches in the push-button circuits, also to prevent interference, arranged to be automatically operated after the motor has started, substantially as described.

26. In an apparatus for controlling elevators, the combination with a motor for operating the car in either direction, of a push-button for each floor or station, push-buttons on the car corresponding to the several floors or stations, circuit-making magnets for the push-button circuits, and a circuit-breaking magnet controlled thereby, whereby the push-button circuits are short-circuited and the floor-push-button circuit broken, to prevent interference, interrupting-switches in the push-button circuits, also to prevent interference, arranged to be automatically operated after the motor has started, and means for preventing the subsequent control of the motor from a floor or station, after it has been operated from the car, and the car has come to rest, substantially as described.

27. In an apparatus for controlling elevators, the combination with a motor for operating the car in either direction, of a push-button for each floor or station, push-buttons on the car corresponding to the several floors or stations, and controlling-circuits and connections between the push-buttons and the motor, so arranged that when any push-button is operated, circuits are completed and the motor operated to bring the car to the station corresponding to the push-button, means in the push-button circuits for short-circuiting the push-buttons when any one is closed, thereby preventing interference, and interrupting-switches in the push-button circuits, also for preventing interference, arranged to be automatically operated after the motor has started, substantially as described.

28. In an apparatus for controlling elevators, the combination with a motor for operating the car in either direction, of a push-button for each floor or station, push-buttons on the car, corresponding to the several floors or stations, circuits and connections including the push-buttons, and motor, a circuit-breaking magnet controlling the floor-push-button circuit, and a safety-magnet included in the car-push-button circuit, and controlling a short circuit to the line, and means for maintaining said short circuit closed after the car has come to rest, subsequent to the operation of the motor from the car, to allow the motor to be controlled from the car, substantially as described.

29. In an apparatus for controlling elevators, the combination with a motor for operating the car in either direction, of a push-button for each floor or station, push-buttons on the car, corresponding to the several floors or stations, circuits and connections including the push-buttons and motor, a circuit-breaking magnet controlling the floor-push-button circuit, and a safety-magnet included

in the car-push-button circuit and controlling a short circuit to the line, and means for maintaining said short circuit closed, both before and after the car has come to rest, subsequent to the operation of the motor from the car, to allow the motor to be controlled from the car, substantially as described.

30. In an apparatus for controlling elevators, the combination with a motor for operating the car in either direction, of a push-button for each floor or station, push-buttons on the car, corresponding to the several floors or stations, circuits and connections including the push-buttons and motor, circuit-making magnets for the push-button circuits, and a circuit-breaking magnet controlled thereby, whereby the push-button circuits are short-circuited and the floor-push-button circuit broken, a safety-magnet included in the car-push-button circuit controlling a short circuit to line, and means for maintaining said short circuit closed both before and after the car has come to rest, subsequent to the operation of the motor from the car, whereby the motor may be controlled from the car only, substantially as described.

31. In an apparatus for controlling elevators, the combination with a motor for operating the car in either direction, of a push-button for each floor or station, and controlling-circuits and connections between the push-buttons and the motor, whereby when any push-button is operated, circuits are closed and the motor operated to bring the car to the station corresponding to the push-button, and means in the controlling-circuits, operated by a motor-reversing switch, for preventing a reversal of the elevator-motor while in operation, substantially as described.

32. In an apparatus for controlling elevators, the combination with a motor for operating the car in either direction, of a push-button for each floor or station, and controlling-circuits and connections between the push-buttons and the motor, whereby when any push-button is operated, circuits are closed and the motor operated to bring the car to the station corresponding to the push-button, and non-interference switches in the motor-controlling circuits for preventing interference with movements of the car while in operation and a reversal of the elevator-motor, substantially as described.

33. In an apparatus for controlling elevators, the combination with a motor for operating the car in either direction, of a push-button for each floor or station, controlling-circuits and connections between the push-buttons and the motor, whereby when any push-button is closed the motor will be operated to bring the car to the desired station, means for automatically closing a circuit around said push-buttons after one of them has been operated, thereby preventing interference with the movements of the car, and additional means in the controlling-circuits, operated

by a motor-reversing switch, for preventing a reversal of the elevator-motor while in operation, substantially as described.

34. In an apparatus for controlling elevators, the combination with a motor for operating the car in either direction, of push-buttons for each floor or station, controlling-circuits and connections between the push-buttons and the motor, whereby when any push-button is closed, the motor will be operated to bring the car to the desired station, means for automatically closing a circuit around said push-buttons after one of them has been operated, thereby preventing interference with the movements of the car, and non-interference switches in the motor-controlling circuits for preventing a reversal of the motor while in operation, substantially as described.

35. In an apparatus for controlling elevators, the combination with a motor for operating the car in either direction, of a push-button for each floor or station, controlling-circuits and connections whereby when any push-button is operated a circuit is closed between the car and the desired floor, and means in the push-button circuits for short-circuiting the push-buttons when any one is closed and thereby preventing interference with the movements of the car, and additional means in the controlling-circuits operated by a motor-reversing switch, for preventing a reversal of the elevator-motor, substantially as described.

36. In an apparatus for controlling elevators, the combination with a motor for operating the car in either direction, of a floor-controller, a push-button for each floor or station, push-buttons on the car corresponding to the floors or stations, a circuit between each push-button and the floor-controller, and means for preventing the completion of a circuit between a floor push-button and the floor-controller, subsequent to the completion of such a circuit from a car push-button, both before and after the car has reached its destination, substantially as described.

37. In an apparatus for controlling elevators, the combination with a motor for operating the car in either direction, of a floor-controller, a push-button for each floor or station, push-buttons on the car corresponding to the floors or stations, a circuit between each push-button and the floor-controller, means between the floor-controller and each push-button for short-circuiting the push-buttons, and means for preventing the completion of a circuit between a floor push-button and the floor-controller, subsequent to the completion of such a circuit from a car push-button, both before and after the car has reached its destination, substantially as described.

38. In an apparatus for controlling elevators, the combination with a motor for operating the car in either direction, of an electric reversing-switch controlling the circuit of the

motor, a floor-controller controlling the operations of the reversing-switch, a push-button for each floor or station, push-buttons on the car corresponding to the floors or stations, a circuit between each push-button and the floor-controller, and means for preventing the completion of a circuit between a floor push-button and the floor-controller, subsequent to the completion of such a circuit from a car push-button, both before and after the car has reached its destination, substantially as described.

39. In an apparatus for controlling elevators, the combination with a motor for operating the car in either direction, of an electric reversing-switch, a floor-controller operated by the motor and controlling the reversing-switch, a push-button for each floor or station, push-buttons on the car corresponding to the floors or stations, a circuit between each push-button and the floor-controller, means in said push-button circuits for closing a circuit around the push-buttons, and means for preventing the completion of a circuit between the floor-controller and a floor push-button, subsequent to the completion of such a circuit from a car push-button, both before and after the car has reached its destination, substantially as described.

40. In an apparatus for controlling elevators, the combination with a motor for operating the car in either direction, of an electric reversing-switch, a floor-controller operated by the motor and controlling the reversing-switch, a push-button for each floor or station, push-buttons on the car corresponding to the floors or stations, circuits between each push-button and the floor-controller, a circuit-making magnet in each push-button circuit, a circuit-breaking magnet controlled by the circuit-making magnets and arranged to cut out the floor-push-button circuits, and means for preventing the completion of a circuit between a floor push-button and the floor-controller, subsequent to the completion of such a circuit from a car push-button, after the car has reached its destination, substantially as described.

41. In an apparatus for controlling elevators, the combination with a motor for operating the car in either direction, of an electric reversing-switch, a floor-controller operated by the motor and controlling the reversing-switch, a push-button for each floor or station, push-buttons on the car corresponding to the floors or stations, circuits between each push-button and the floor-controller, a circuit-making magnet in each push-button circuit, and a circuit-breaking magnet controlled by the circuit-making magnets and arranged to cut out the floor-push-button circuits, an automatic interrupting-switch for cutting out the car-push-button circuits, and means for preventing the completion of a circuit between the floor-controller and a floor push-button subsequent to the completion of such a

circuit from a car push-button, after the car has reached its destination, substantially as described.

42. The combination of a motor for operating the car in either direction, motor-controlling devices connected to the car and stations, non-interference devices for preventing the controlling devices connected to the car from being operated by those connected to the stations, and interrupting-switches in the controlling-circuits arranged to be operated as the motor is started, substantially as described.

43. The combination of a motor for oper-

ating the car in either direction, motor-controlling devices connected to the car and stations and interrupting-switches controlling said controlling devices and in turn controlled by the operation of the motor, substantially as described.

In testimony whereof I have signed my name to this specification in the presence of two subscribing witnesses.

JOHN D. IHLDER.
